UNITED STATES PATENT OFFICE.

HENRY L. HOFFMANN, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 22, 1923. Serial No. 682,198.

To all whom it may concern:

Be it known that I, HENRY L. HOFFMANN, a citizen of the United States of America, residing at East Orange, in the county of 5 Essex and State of New Jersey, have invented certain new and useful Improvements in Telephone Systems, of which the following is a full, clear, concise, and exact description.

10 This invention relates to telephone exchange systems, and more particularly, to improvements in the trunk circuit for establishing a connection between manual exchanges.

15 The invention is adapted for use in systems in which calls received at a manual switchboard at one exchange are extended by means of so called A operator's link circuits and trunk lines terminating at another 20 exchange and from there by means of so called B operator's link circuits at this latter exchange to a desired subscriber's line.

In such systems a number of trunk circuits and a number of B operator's link circuits 25 are usually provided and any one of the link circuits may be used for extending the connection to the wanted subscriber by inserting one plug thereof in the jack of a chosen trunk and the other plug in the jack of a 30 wanted subscriber's line and the B operator's telephone set is manually connected to such a link circuit by means of a key. The trunk used is ordinarily assigned by the aid of a separate call wire circuit extending between 35 the two exchanges which is available for this purpose to the operators at the two positions.

An object of this invention is to eliminate 40 the use of call wire circuits to assign trunk lines by the provision of a so called "straight forward" trunking system embodying means whereby the A operator may connect with any one of the trunk lines leading to the exchange in which the wanted subscriber's line 45 terminates and whereby the B operator may select any available link circuit and by manually connecting it to the wanted subscriber's line automatically extend the connection from the seized trunk line to the wanted subscriber.

Another object is to automatically connect 50 the B operator's telephone equipment with a trunk line the moment it is seized by the A operator.

55 Another object is to automatically discon-

nect the B operator's telephone equipment from such a seized trunk line at the moment the selected link circuit is manually connected to the wanted subscriber's line and automatically connected to the seized trunk. 60

Another object is to transmit various supervisory signals between the two operator's positions for the purpose of controlling the connection during the setting up operations as well as during the conversation or at the 65 release of the connection.

Another object is to automatically ring a wanted subscriber's line when the connection is completed.

Another object is to provide means whereby if the B operator transfers a connection from one seized outgoing line to another as, for example, from a line terminating in a supervisory or monitoring board to a line terminating at a substation, said second line 75 is automatically rung in a manner similar to that in which the first line was called. 70

To attain these objects in accordance with one feature of the invention the incoming trunk lines and the B operator's link circuits 80 terminate in switching devices by means of which any link circuit taken for use may be automatically associated with the seized trunk line the moment it is manually connected to the wanted subscriber's line. 85

Another feature is the provision of an arrangement including a second switching device which is actuated the moment a trunk circuit is seized by the A operator to connect the B operator's telephone equipment with 90 said trunk line and a circuit arrangement for automatically disconnecting this equipment from the trunk line the moment the manual connection to the wanted subscriber is completed. 95

Another feature resides in the provision of signaling means whereby the B operator is notified when the trunk circuit has been seized for the extension of a call and when her telephone equipment is connected to or 100 disconnected from the seized trunk line.

Another feature is the provision of means whereby the B operator may test the wanted subscriber's line for a busy condition without causing the selected link circuit to connect with the seized trunk line and whereby if the subscriber's line is busy, she may send a distinctive signal over the seized trunk line to the A operator to call her attention to 105 this condition. 110

Another feature is the provision of a signaling means whereby if the B operator disconnects accidentally or otherwise, the link circuit connected to the wanted subscriber's line before the A operator is disconnected from the trunk line the B operator is notified in a distinctive manner of this fact.

Another feature is the provision of a signaling means whereby the B operator receives a distinctive signal if the A operator disconnects her link circuit from the seized trunk line.

Another feature is the provision of means for ringing the wanted subscriber's line automatically when the link circuit is connected to such line and ringing a second subscriber's line when the link circuit is transferred thereto while the A operator is still connected to the seized trunk line and without disconnecting the link circuit from said trunk line.

Another feature of the invention is the provision of means whereby the A operator receives a distinctive signal if she has connected with a trunk terminating at an unattended B operator's position.

One embodiment of the invention is illustrated in the accompanying drawings in which Fig. 1 shows an A operator's link circuit at one manual exchange; a manual subscriber's line terminating thereat and the terminating end of a trunk line leading to another exchange.

Fig. 2 shows the incoming end of said trunk line in another manual exchange and a B operator's link circuit and telephone equipment embodying the features of this invention and also a wanted subscriber's line terminating thereat.

Referring now to the drawings a calling subscriber's line 1 terminates in jack 2 in a manual switchboard and an A operator's link circuit may be employed to connect line 1 with trunk line C terminating in a jack 16 and extending from there to another manual exchange where it may be connected through the medium of switch 80 to a B operator's link circuit D, which link circuit, in turn, may be connected by means of plug 65 to a jack 66 of a wanted subscriber's line 100. The trunk line C, which may be one out of a group of similar trunk lines extending between the two exchanges, may be connected in common with such trunks to the bank terminals of switch 80 as shown, and it is understood that these trunks may also be multiplied to the bank terminals of a number of other similar switches and the movable terminals of each switch connected to a separate link circuit such as D. Such a group of link circuits may then be located in a manual switchboard available to a B operator as is the practice where ordinary B operator's link circuits are used. The B operator's

telephone equipment shown below the dotted line in Fig. 2 is common to these trunk lines and link circuits and may be associated with any one of the trunk lines by means of a common relay arrangement and a switch 60. As the construction of the switches 80 and 60 forms no part of this invention no detail description will be given except to say that they may be of the well known finger type, the brushes or movable terminals of which may be moved in a step-by-step fashion. The brushes of switch 80 may be moved by the stepping magnet 69 and the brushes of the switch 60 may be moved by means of the stepping magnet 44 and as these switches have no normal position the brushes will remain on the terminals to which they were last advanced.

The invention is best understood by describing the setting up of a connection between a calling subscriber's line 1 and a called subscriber's line 100 by means of the arrangement shown in the drawings and such a connection will now be described.

Assuming that the subscriber on line 1 has initiated a call in the usual manner and that A operator has answered it by the insertion of plug 3 in jack 2 and connected her telephone set to the link circuit A by the operation of listening key 10 and received from the calling subscriber the number of the wanted subscriber, she proceeds by inserting the calling plug 15 in a jack such as 16 of any link circuit such as C leading to the exchange in which the wanted subscriber's line 100 terminates. It will be observed that it is not necessary for the A operator to have any particular trunk line leading to the desired exchange assigned her, but she may, on the contrary, connect with any of the trunks at the moment most conveniently at hand. When, therefore, a connection to any one of the trunks is completed as in this case to trunk line C, circuits are established to connect the B operator's telephone equipment to this selected trunk as follows: The first circuit is completed from battery at the A operator's link circuit, the lower right hand winding of repeating coil 17, supervisory relay 18, ring contacts of plug 15 and jack 16, lower left hand winding of repeating coil 30, left hand winding of relay 40, upper left hand winding of repeating coil 30, tip contacts of jack 16 and plug 15, upper right hand winding of repeating coil 17 to ground. This circuit energizes relay 18 to cause the shunting and extinguishment of the supervisory lamp 19 in a well known manner and at the distant exchange energizes relay 40. The operation of relay 40 establishes a circuit for relays 41 and 42 from battery, armature and contact of relay 40, outer left hand armature and back contact of relay 91, make before break contacts of relay 71, winding

115
120
125
130

of relay 41, resistance 77, winding of relay 42 to ground.

The operation of relay 42 closes a circuit for lamp 43 over an obvious circuit to notify the B operator that a connection is desired, and this relay also closes a circuit for the stepping magnet 44 from battery, winding of stepping magnet 44, armature and back contact of this magnet, right hand armature and front contact of relay 42, left hand armature and back contact of relay 45 to ground. The stepping magnet 42 now through its self-interrupting contacts is caused to vibrate and in the well known manner in switches of this type advances thereby the brushes 50 and 51 in a step-by-step fashion to hunt for the selected trunk line C and when brush 50 finds the terminal 52 in its contact bank which represents trunk C a circuit is completed from battery at 40 as previously traced to the point 53, and from there to terminal 52, brush 50, winding of relay 45 to ground. This circuit causes the operation of relay 45 and the deenergization of marginal relay 42 as this path to ground from the battery of relay 40 is one of less resistance than that through the resistance 77 and winding of relay 42. The release of relay 42 causes lamp 43 to be extinguished and the operation of relay 45 causes the lamp 46 to be lighted over an obvious circuit, the extinguishing of lamp 43 and lighting of lamp 46 indicating to the B operator that the trunk C has been found, and that her telephone set will presently be connected thereto.

The release of relay 42 and the operation of relay 45 open the circuit for the stepping magnet 44; the relay 42 at its right-hand armature and front contact and relay 45 at its left-hand armature and back contact, causing the magnet 44 to become deenergized and the brushes 50 and 51 thereby permitted to come to rest on the contacts corresponding to the trunk C. The purpose of brush 51 and the corresponding terminals will be described hereinafter. The operation of relay 41 extends at its inner left-hand armature and front contact and at its right-hand armature and front contact a circuit from trunk C to the inner lower armature and upper armature of relay 47, which relay is momentarily energized by a circuit closed by the energization of relay 45 as follows: battery, winding of relay 47, armature and back contact of relay 49, left-hand armature and front contact of relay 45 to ground.

The energization of relay 47 extends the leads previously mentioned from the trunk C to a tone producing device which thereby is connected to the A operator's telephone set to notify her that the B operator's device is about to be connected. This tone circuit may be traced as follows: battery, lower

right-hand winding of repeating coil 30, winding of relay 84, right-hand armature and back contact of relay 91, inner left-hand armature and front contact of relay 41, inner lower armature and front contact of relay 47, through the secondary of the tone producing device AT to upper armature and front contact of relay 47, right-hand armature and front contact of relay 41, upper right-hand winding of repeating coil 30 to ground, and the repeated circuit through the left-hand windings of the repeating coil 30, through the trunk C, jack 16, plug 15, listening key 10 to the operator's telephone set.

As stated this circuit is only maintained for a short interval as the operation of relay 47 extends an energizing circuit for relay 48 as follows: battery, upper winding of relay 48, outer lower armature and front contact of relay 47, armature and back contact of relay 49, left-hand armature and front contact of relay 45 to ground. Relay 48 is thereby operated and locks up to ground at relay 45 and at the same time causes the energization of relay 49 over a circuit from battery, lower winding of relay 48, outer lower armature and front contact of this relay, winding of relay 49, left-hand armature and front contact of relay 45 to ground, and the operation of relay 49 at its armature and back contact causes the release of relay 47. The release of relay 47 and the operation of relay 48 now, therefore, removes the tone producing device AT from the circuit to the A operator's telephone set and extends this circuit to the B operator's telephone set OT as follows: The relay 47 at its inner lower armature and back contact and upper armature and back contact and the relay 48 at its inner lower armature and front contact and upper armature and front contact. The A operator on noticing the tone may therefore immediately transmit to the B operator the number of the wanted subscriber and then release her listening key 10 and pays no further attention to the connection until it has been extended or until it is ready for release, of which she will be notified either by distinct signals that the connection has been completed or that the wanted subscriber's line is busy or that the conversation between the subscribers is at an end.

As soon as the B operator receives the number of the wanted subscriber she proceeds to complete the connection as follows: She may select out of a number of link circuits, such as D any most conveniently at hand and test the wanted subscriber's line in the usual manner by touching the sleeve of the jack with the tip of the selected plug 65 and thus if the wanted subscriber is busy cause the operation of the usual busy tone device SBT associated with her position. If the B operator receives such

- a busy tone she will immediately notify the A operator of this fact by depressing a key such as 61 or 62 whichever is most conveniently at hand, one of these keys being located on the right hand side and the other on the left hand side of the position. The depression of one of these keys, for example 62, causes busy signal indications to be transmitted to the A operator by the following circuit from battery, armature and front contact of relay 40, winding of relay 91, bank terminal 92 and brush 51 of switch 60, key 62 to ground. This circuit causes the operation of relay 91 which now locks up through its own inner left-hand armature and front contact to ground from the battery at relay 40. The operation of relay 91 extends the busy signal circuit to the A operator's position as follows: from battery, lower right-hand winding of repeating coil 30, winding of relay 84, right-hand armature and front contact of relay 91, key 90, secondary winding of the busy tone producing device BBT interrupter 93 to ground. This circuit through the interrupter 93 causes the alternate operation and release of relay 84 which thereby opens and closes at its armature and front contact a shunt circuit through the right-hand winding of relay 40. The inclusion of this shunt winding across the conductors of trunk line C causes the alternate release and operation of the supervisory relay 18 and the consequent flashing of lamp 19 in the well known manner. It will also be noted that if the operator has not yet disconnected her telephone from the link circuit A by the release of listening key 10, she will at this time in addition to the flashing signal also receive a busy tone signal in her receiver as the busy tone producing device BBT has as stated its secondary winding included in the above traced circuit as shown, this arrangement being provided as an additional means for the speeding up of the service. These signals continue to operate until the A operator removes her plug 15 from the jack 16.
- It should also be noted that the B operator's telephone is immediately removed from the trunk line at the operation of key 62 as the relay 91 at its outer left-hand armature and back contact opens the circuit for relays 45 and 41. The release of relay 45 causes the lamp 46 to be extinguished and relays 49 and 48 to be released, and the release of relays 48 and 49 cause the B operator's telephone equipment to be disconnected from the trunk line C.
- On the other hand, in case the wanted subscriber is not busy the B operator will complete the connection by inserting plug 65 fully into the jack 66 and thus cause relay 67 to be energized over an obvious circuit. The operation of relay 67 immediately causes the lighting of lamp 68 over a circuit from battery, armature and back contact of relay 94, lamp 68, second lower armature and front contact of relay 67, outer right-hand armature and back contact of relay 70 to ground to indicate to the B operator that the line is functioning. The operation of this relay 67 also causes the finder switch 80 associated with this link circuit D to begin its hunting operations for the selected trunk line C and to this end a circuit is completed for the step-by-step magnet 69 as follows: battery, third lower armature and front contact of relay 67, winding of magnet 69, the armature and back contact of this magnet, inner right-hand armature and back contact of relay 70 and make before break contacts of relay 73 to ground. The stepping magnet 69 operates in a step-by-step manner by interrupting its own contacts and thus advances in the well known manner the movable brushes 81, 82 and 83 of the switch 80 until the brushes 81 and 82 come in contact with the terminals of trunk C and brush 83 comes in contact with terminal 84, which latter connection closes a circuit from battery, at the outer left-hand armature and front contact of relay 41, which it will be remembered was energized at the time the trunk circuit C was seized, through the winding of relay 71, the above mentioned contact 84 and brush 83, left-hand armature and back contact of relay 73, left-hand winding of relay 70 and inner lower armature and front contact of relay 67 to ground. This circuit causes the operation of relays 71 and 70. Relay 71, in operating, substitutes in this circuit for the battery at the outer left-hand armature and front contact of relay 41 the battery at relay 40 and by means of its contacts, opens the holding circuit for relays 41 and 45 and thus causes the immediate disconnection of the B operator's telephone equipment from the trunk line C as previously explained. The operation of relay 70, on the other hand, opens at its inner right-hand armature and back contact the circuit for the stepping magnet 69, causing the switch 80 to stop with the brushes 81 and 82 in connection with the trunk line C and the brush 83 remaining in contact with the terminal 84. This relay 70 also causes the operation of relay 73 over a circuit from battery, third lower armature and front contact of relay 67 right-hand winding of relay 73 inner right-hand armature and front contact of relay 70, right-hand make-before-break contacts of relay 73 to ground, causing relay 73 to lock up over an obvious circuit via its inner right hand armature and a make-before-break contact thereof to ground, and also over its left-hand armature and front contact and the right-hand winding of relay 70 to ground. Relay 70 being thereby

locked up in series with relay 73 to battery of relay 40 independent of the ground at the inner lower armature and front contact of relay 67. The purpose of this relay 5 operation will become apparent as the description proceeds.

It is further noticed that relay 70 opens at its outer right-hand armature and back contact the circuit for the lamp 68 which 10 is thereby extinguished to indicate to the B operator that the link circuit D is about to be connected to the trunk line C and that automatic ringing of the wanted subscriber has been applied as a circuit was completed 15 at the outer right-hand armature and front contact of relay 70 at its energization for relay 72 as follows: battery, armature and back contact of ringing relay 74, outer lower armature and back contact of relay 75, 20 winding of relay 72, fourth lower armature and front contact of relay 67, outer right-hand armature and front contact of relay 70 to ground. This circuit causes the operation of relay 72 and ringing current is therefore applied from the source 76 through the winding of ringing relay 74, inner lower armature and back contact of relay 75, lower armature and front contact of relay 72, ring contacts of plug 65 and jack 66, through 25 the wanted subscriber's bell, back through the tip contacts of jack 66 and plug 65, upper armature and front contact of relay 67, upper armature and front contact of relay 72, upper armature and back contact of relay 30 75 to ground. When the called subscriber answers in the usual manner by lifting his receiver from the hook, relay 74 operates and disconnects the battery at its armature and back contact from the circuit 35 for relay 72, which now receives a substitute battery through the winding of relay 75 formerly shunted by the first mentioned battery, causing relay 75 to operate to open the ringing circuit at its upper armature 40 and back contact and inner lower armature and back contact and substituting therefor at its upper armature and front contact and inner lower armature and front contact the 45 leads connecting the brushes 81 and 82 with the conductors of the trunk line C. The 50 calling subscriber at station 1 is now, therefore, connected through to the called subscriber and conversation may take place. The A operator is notified of this fact by 55 the operation of relay 84 the moment relay 75 is operated, as relay 84 in operating causes the right-hand winding of relay 40 to be shunted across the conductors of the 60 trunk C to operate relay 18 and extinguish lamp 19.

The release of the connection may be initiated by either subscriber replacing his receiver on the hook. If the calling subscriber hangs up lamp 5 will be lighted or 65 if the called subscriber hangs up lamp 19

will be lighted by the release of relay 84 in the well known manner. In either case it is the duty of the A operator to release the connection by removing the plugs 3 and 15 from jacks 2 and 16, respectively, and when 70 the trunk line C is thus released relay 40 is released, causing the release of relays 71 and 70 which as previously explained were held operated by the battery at the contacts of relay 40. Relay 70, in releasing, 75 causes the release of relays 72 and 75, thus opening the connection of the link circuit to the trunk line C. The release of relay 70 also causes lamp 68 to be lighted to maintain a steady glow by closing a circuit at the 80 outer right-hand armature and back contact to ground for this lamp from battery at the armature and back contact of relay 94 if the wanted subscriber has in the meantime hung up his receiver, thus notifying the B operator that the A operator has released the connection and the B operator will now remove her plug 65 from jack 66, thus releasing relay 67, extinguishing the 85 lamp 68 and releasing relay 73. 90

On the other hand if the called subscriber has not replaced his receiver, the B operator will be apprised to remove plug 65 from jack 66 as follows: Relay 94 will be operated when relay 72 is released by a circuit from battery through its right-hand winding lower armature and back contact of relay 72 through the called subscriber's loop back to the upper armature and back contact of relay 72 left hand winding of 100 relay 94 to ground, and thus connect the interrupter 96 to the circuit for lamp 68 which will then indicate this fact to the B operator by a flashing signal. Should the subscriber at this moment and prior to the 105 removal of plug 65 from jack 66 by the B operator, notice that he had been disconnected, desire to reestablish the connection he will move his receiver up and down and thus alternately cause the lamp 68 to 110 flash or burn with a steady glow and thus indicate to the B operator that he desires the connection to be reestablished.

In case of accidental removal of plug 65 from jack 66 before either of the subscribers desires a connection to be released, the signal 68 is automatically flashed to indicate this fact to the B operator as follows: Relay 67 is released whereas relay 73 is still held operated by the holding circuit from 115 battery at relay 40 and a circuit for the lamp 68 is, therefore, completed from battery, armature and back contact of relay 94, lamp 68, second lower armature and back contact of relay 67, outer right-hand 120 armature and front contact of relay 73, interrupter 76 to ground. When the B operator receives this flashing signal she immediately again inserts the plug 65 in jack 125 66 and thus restores the connection to nor 130

mal. The release of relay 67 in this case will also cause the temporary release of relays 72 and 75 as the circuit for these relays are controlled by the fourth lower 5 armature and front contact of relay 67, and if the subscriber 100 had in the meantime hung up his receiver, he would again be called by the connection of the ringing source 76 as previously explained.

10 In case the operator had first inserted the plug 65 in the jack of the line leading to a supervisory's or monitor's board to permit the calling subscriber to obtain special information and then later removed the 15 plug 65 therefrom and inserted it in the wanted subscriber's jack, lamp 65 and the reringing operation will be exactly the same, as in the case of the accidental removal of the plug 65 from the jack 66.

20 In other words, the arrangement is such that the plug 65 can be transferred from one jack to another and the ringing operations repeated each time to call the party upon the line connected with at the moment.

25 An arrangement is also provided whereby in case the B operator's position has to be left unattended, a signal is transmitted to the A operator's position when she has seized the trunk leading to this operator's 30 position, and to this end key 90 may be depressed and locked to connect the busy tone device OBT to the seized trunk. When, therefore, a trunk C is seized, switch 60 operates, as hereinbefore described, to find 35 the B operator's equipment, but instead of functioning to connect her telephone set, the relay 91 operates over a circuit from battery, armature and front contact of relay 40, winding of relay 91, stationary terminal 40, movable terminal 51, lower operated contacts of key 90 to ground, and relay 91 is thereby locked up from battery at relay 40 through its inner left hand armature and front contact to ground. The operation of 45 relay 91 breaks at the outer left hand armature and back contact the energizing circuit for relays 42 and 45, preventing the B operator's telephone set from being connected to the seized trunk, and by the operation 50 of its right hand armature and front contact closes a circuit for the busy tone device OBT as follows: from battery, lower right hand winding of repeating coil 30, winding of relay 84, right hand armature 55 and front contact of relay 91, upper operated contacts of key 90, secondary winding of the busy tone device OBT to ground. The busy tone is thus transmitted to the repeating coil 30 and repeated to the A operator's telephone set over a circuit, as 60 previously described, to indicate to the A operator that the B operator's position is unattended. When the A operator disconnects her plug 15 from the seized trunk jack 16, relays 40 and 91 are released.

What is claimed is:

1. A telephone system comprising trunk lines, an operator's telephone set, a first subscriber's line, means responsive to the connection of said first subscriber's line to any one of said trunks to connect the operator's telephone set thereto, a second subscriber's line, a link circuit for connecting to said second subscriber's line, and means operative upon the connection of said link circuit to said second subscriber's line to connect said link circuit to the said trunk circuit:

2. A telephone system comprising trunk lines, an operator's telephone set, a calling line, means for connecting any one of said trunks to said calling line, an electromagnetic means operative when a trunk is seized to connect the operator's telephone set thereto, other subscribers' lines, a link circuit for connecting with any one of said other subscribers' lines, and a second electromagnetic means operative responsive to the connection of said link circuit to one of said other subscribers' lines for connecting the link circuit to the trunk line.

3. A telephone system comprising trunk lines, an operator's telephone set, means for seizing any one of said trunks, a finder switch responsive thereto for connecting the operator's telephone set to the seized trunk, subscribers' lines, a link circuit for connecting with any one of said subscribers' lines, and a second finder switch responsive to the seizing of a subscriber's line by the link circuit and the seizure of the trunk line for connecting the link circuit to the trunk line.

4. A telephone system comprising trunk lines, an operator's telephone set, means for seizing any one of said trunks, automatically operated means responsive thereto for connecting the operator's telephone set to the seized trunk, subscribers' lines, a link circuit for connecting with any one of said subscribers' lines, and a second automatically operated means responsive to the seizure of the subscriber's line by the link circuit and the seizure of the trunk circuit for associating the link circuit with the seized trunk line.

5. A telephone system comprising trunk lines, an operator's telephone set, a first subscriber's line, means for connecting any one of said trunks to said first subscriber's line, means for automatically connecting the operator's telephone set to a trunk line when said trunk line is so seized, subscribers' lines, a link circuit for connecting with any one of said subscribers' lines, means for automatically connecting the link circuit to said seized trunk line when the link circuit has seized a subscriber's line.

6. A telephone system comprising trunk lines terminating at one end in jacks, a link circuit having a plug adapted for connection

- with the jack of any one of said trunk lines, an automatic switch in which the other end of said trunk lines terminate, a second link circuit terminating at one end in said switch 5 and at the other end in a plug, subscribers' lines having jacks for the connection with the plug of the link circuit, an operator's telephone equipment, means including a switch for connecting automatically the operator's telephone equipment with a trunk line having been seized by said first mentioned link circuit, and means associated with said second link circuit for operating said first mentioned switch to connect this 15 link circuit with said seized trunk line when said link circuit has seized a subscriber's line.
7. A telephone system comprising trunk lines, an operator's telephone set, a first subscriber's line, means for connecting any one of said trunks with said first subscriber's line, means operative when a trunk is so seized to connect the operator's telephone set thereto, other subscribers' lines, a link circuit for connecting with any one of said other subscribers' lines, means operative responsive to the connection of said link circuit to one of said other subscribers' lines to connect the link circuit with said trunk line, and means operative when said other subscriber's line is seized for disconnecting the operator's telephone set from the seized trunk line.
8. A telephone system comprising trunk lines, an operator's telephone set, a first subscriber's line, means for connecting any one of said trunks to said first subscriber's line, means operative when a trunk is so seized to connect the operator's telephone set thereto, other subscribers' lines, a link circuit for connecting with any one of said other subscribers' lines, means operative responsive to the connection of said link circuit to one of said other subscribers' lines to connect the link circuit with the trunk line, and means operated when the link circuit is connected to the seized trunk line to disconnect the operator's telephone set therefrom.
9. A telephone system comprising trunk lines, an operator's telephone set, a first subscriber's line, means for connecting any one of said trunks with said first subscriber's line, means operative when a trunk is so seized to connect the operator's telephone set thereto, means to indicate the seizure of a trunk, other subscribers' lines, a link circuit for connecting with any one of said other subscribers' lines, and means operative responsive to the connection of said link circuit to one of said other subscribers' lines to connect the link circuit with the trunk line.
10. A telephone system comprising trunk lines, an operator's telephone set, a first subscriber's line, means for connecting any one of said trunks with said first subscriber's line, means operative when a trunk is so seized to connect the operator's telephone set thereto, other subscribers' lines, a link circuit connected with any one of said other subscribers' lines, and means operative responsive to the connection of said link circuit with one of said other subscribers' lines to connect the link circuit with the trunk line.
11. A telephone system comprising trunk lines, an operator's position at one end of said trunks, a first subscriber's line terminating at said position, an operator's position at the other end of said trunks, means at the first mentioned operator's position for connecting any one of said trunks, means operative when a trunk is seized to connect the second mentioned operator's telephone equipment thereto, means for indicating to the first mentioned operator when the second mentioned operator's equipment is associated with the seized trunk, other subscribers' lines, a link circuit at the second operator's position for connecting with any one of said other subscribers' lines, and means operated responsive to the connection of said link circuit to one of said other subscribers' lines to connect the link circuit with said trunk line.
12. A telephone system comprising trunk lines, an operator's position at one end of said trunks, an operator's position at the other end of said trunks, means at the first mentioned operator's position for seizing any one of said trunks, means operative when a trunk is seized for connecting the second mentioned operator's telephone equipment thereto, a means operated in response to the connection of the second mentioned operator's equipment to the seized trunk to transmit a momentary signal to the first mentioned operator's position over said seized trunk, subscribers' lines, a link circuit for connecting with any one of said subscribers' lines, and means operative when a trunk line and a subscriber's line are seized to connect the link circuit with the trunk line.
13. A telephone system comprising trunk lines, an operator's position at one end of said trunks, an operator's position at the other end of said trunks, means at the first mentioned operator's position for seizing any one of said trunks with said first subscriber's line, means operative upon the seizure of said trunk to connect the second mentioned operator's telephone set thereto, a signaling means associated momentarily with a trunk when it is seized to transmit to the first mentioned operator's position an audible signal to indicate that the second mentioned operator's telephone set is about to be connected therewith, subscribers' lines,

- 5 a link circuit for connecting with any one of said subscribers' lines, and means operative when the trunk line and a subscriber's line are seized to connect the link circuit with the 5 trunk line.
- 10 14. A telephone system comprising trunk lines, an operator's position at one end of said trunks, an operator's position at the other end of said trunks, means at the first mentioned operator's position for seizing any one of said trunks, means operative when a trunk is seized to connect the second mentioned operator's equipment thereto, a signaling means associated with the trunk in 15 response to its seizure to transmit to the first mentioned operator's position an audible signal and disassociated from the trunk when the second mentioned operator's equipment is connected to said seized trunk, subscribers' 20 lines, a link circuit for connecting with any one of said subscribers' lines, and means operative when the trunk line and a subscriber's line are seized to connect the link circuit with the trunk line.
- 25 15. A telephone system comprising trunk lines, an operator's telephone set, means for seizing any one of said trunks, means operative when a trunk is seized to connect the operator's telephone set thereto, subscribers' 30 lines, a link circuit for connecting with any one of said subscribers' lines, means operative responsive to the seizure of said trunk line and said subscriber's line to connect the link circuit with the trunk line, and means 35 associated with the link circuit operative when the subscriber's line is seized to indicate to the operator that the subscriber's line is not otherwise engaged.
- 40 16. A telephone system comprising trunk lines, an operator's telephone set, means for seizing any one of said trunks, means operative when a trunk is seized to connect the operator's telephone set thereto, subscribers' lines, a link circuit for connecting with any 45 one of said subscribers' lines, means operative when the trunk line and a subscriber's line are seized to connect the link circuit with the trunk line, and a visual signal in said link circuit operated when a subscriber's line is seized to indicate that the subscriber's line is not otherwise engaged.
- 50 17. A telephone system, comprising trunk lines, an operator's telephone set, means for seizing any one of said trunks, means operative when a trunk is seized to connect the operator's telephone set thereto, subscribers' lines, a link circuit for connecting with any 55 one of said subscribers' lines, means operative when the trunk line and a subscriber's line are seized to connect the link circuit with the trunk line, and a visual signal in said link circuit operated when a subscriber's line is seized and before the trunk line is connected to the link circuit.
- 60 18. A telephone system comprising trunk lines, an operator's telephone set, means for seizing any one of said trunks, means operative when a trunk is seized to connect the operator's telephone set thereto, subscribers' lines, a link circuit for connecting with any 65 one of said subscribers' lines, means operative when the trunk line and a subscriber's line are seized to connect the link circuit with the trunk line, and an intermittently operated signal actuated when the link circuit is disconnected from the subscriber's line but still connected to the seized trunk line.
- 70 19. A telephone system comprising trunk lines, an operator's telephone set, means for seizing any one of said trunks, means operative when a trunk is seized to connect the operator's telephone set thereto, subscribers' lines, a link circuit for connecting with any 75 one of said subscribers' lines, means operative when the trunk line and a subscriber's line are seized to connect the link circuit with the trunk line, means for disconnecting the link circuit from a trunk line when said trunk line is released, and signaling means operative when a link circuit is released to indicate to the operator that such a release has taken place.
- 80 20. A telephone system comprising trunk lines, an operator's telephone set, means for seizing any one of said trunks, means operative when a trunk is seized to connect the operator's telephone set thereto, subscribers' lines, a link circuit for connecting with any 85 one of said subscribers' lines, means operative when the trunk line and a subscriber's line are seized to connect the link circuit with the trunk line, means for disconnecting the link circuit from a trunk line 90 when said trunk line is released, and a signal intermittently operated when the link circuit is released.
- 90 21. A telephone system comprising trunk lines, an operator's telephone set, means for seizing any one of said trunks, means operative when a trunk is seized to connect the operator's telephone set thereto, subscribers' lines, a link circuit for connecting with any 95 one of said subscribers' lines, means operative when the trunk line and a subscriber's line are seized to connect the link circuit with the trunk line, and an indicating means 100 operative when the link circuit is disconnected from the subscriber's line but still connected to the seized trunk line.
- 100 22. A telephone system comprising trunk lines, an operator's telephone set, means for seizing any one of said trunks, means operative when a trunk is seized to connect the operator's telephone set thereto, subscribers' lines, a link circuit for connecting with any 105 one of said subscribers' lines, means operative when the trunk line and a subscriber's line are seized to connect the link circuit with the trunk line, and an intermittently operated signal actuated when the link circuit is disconnected from the subscriber's line but still connected to the seized trunk line.
- 110 23. A telephone system comprising trunk lines, an operator's telephone set, means for seizing any one of said trunks, means operative when a trunk is seized to connect the operator's telephone set thereto, subscribers' lines, a link circuit for connecting with any 115 one of said subscribers' lines, means operative when the trunk line and a subscriber's line are seized to connect the link circuit with the trunk line, and an intermittently operated signal actuated when the link circuit is disconnected from the subscriber's line but still connected to the seized trunk line.
- 120 24. A telephone system comprising trunk lines, an operator's telephone set, means for seizing any one of said trunks, means operative when a trunk is seized to connect the operator's telephone set thereto, subscribers' lines, a link circuit for connecting with any 125 one of said subscribers' lines, means operative when the trunk line and a subscriber's line are seized to connect the link circuit with the trunk line, and an intermittently operated visual signal actuated when the link circuit 130

is disconnected from the subscriber's line but still connected to the seized trunk line.

23. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, means for indicating to the operator when a subscriber's line is busy, and means under control of the operator for transmitting a signal over the seized trunk line to indicate at the opposite end of the trunk line that a subscriber's line is busy and for disconnecting the operator's telephone set from the seized trunk.

10 24. A telephone system comprising trunk lines, an operator's position at one end of the trunk line, an operator's position at the other end of said trunk line, means at the first operator's position for seizing any one of said trunk lines, means operative when a trunk line is seized to connect the second operator's equipment thereto, subscribers' lines, a link circuit for connecting with any one of said subscribers' lines, means operative when a trunk line and a subscriber's line are seized to connect the link circuit with the trunk line, means for testing a subscriber's line as to its busy condition without causing the connection of the link circuit with the seized trunk line, and signaling means under control of the second operator for notifying the first operator that a subscriber's line is busy.

20 25. A telephone system comprising trunk lines, an operator's position at one end of said trunk line, an operator's position at the other end of said trunk line, means at the first operator's position for seizing any one of said trunk lines, means operative when a trunk line is seized to connect the second operator's equipment thereto, subscribers' lines, a link circuit for connecting with any one of said subscribers' lines, means operative when the trunk line and a subscriber's line are seized to connect the link circuit to the trunk line, means for testing a subscriber's line as to its busy condition without causing the connection of the link circuit with the seized trunk line, and signaling means under control of the second operator for notifying the first operator that a subscriber's line is busy.

25 26. A telephone system comprising trunk lines, an operator's position at one end of said trunk line, an operator's position at the other end of said trunk line, means at the first operator's position for seizing any one of said trunk lines, means operative when a trunk line is seized to connect the second operator's equipment thereto, subscribers' lines, a link circuit for connecting with any one of said subscribers' lines, means operative when the trunk line and a subscriber's line are seized to connect the link circuit with the trunk line, means for testing a subscriber's line as to its busy condition without causing the connection of the link circuit with the seized trunk line, a signaling means comprising a device for transmitting a tone, a device for simultaneously transmitting an interrupted signal and a key under the control of the second operator, to notify the first operator that a subscriber's line is busy.

30 27. A telephone system comprising trunk lines, an operator's position at one end of said trunk line, an operator's position at the other end of said trunk lines, means at the first operator's position for seizing any one of said trunk lines, means operative when a trunk line is seized to connect the second operator's equipment thereto, subscribers' lines, a link circuit for connecting with any one of said subscribers' lines, means operative when a trunk line and a subscriber's line are seized to connect the link circuit with the seized trunk line, signaling means under control of the second operator for notifying the first operator that a subscriber's line is busy, and means under control of the second operator for disconnecting her telephone equipment from the seized trunk line simultaneously with the operation of the said signaling means.

35 28. A telephone system comprising trunk lines, an operator's position at one end of said trunk line, an operator's position at the other end of said trunk lines, means at the first operator's position for seizing any one of said trunk lines, means operative when a trunk line is seized to connect the second operator's equipment thereto, subscribers' lines, a link circuit for connecting with any one of said subscribers' lines, means operative when the trunk line and a subscriber's line are seized to connect the link circuit with a trunk line, and means at the second operator's position to prevent the connection of her equipment to the seized trunk line and to transmit a signal to the first operator's position over said trunk line to indicate that said second operator's position is unattended.

40 29. A telephone system comprising trunk lines, an operator's position at one end of said trunk lines, an operator's position at the other end of said trunk lines, means at the first operator's position for seizing any one of said trunk lines, means operative when a trunk line is seized to connect the second operator's equipment thereto, subscribers' lines, a link circuit for connecting with any one of said subscribers' lines, means operative when a trunk line and a subscriber's line are seized to connect the link circuit with the seized trunk line, signaling means under control of the second operator for notifying the first operator that a subscriber's line is busy, and means under control of the second operator for disconnecting her telephone equipment from the seized trunk line simultaneously with the operation of the said signaling means.

45 30 31. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when a trunk line and a subscriber's line are seized to connect the link circuit with the seized trunk line, signaling means under control of the second operator for notifying the first operator that a subscriber's line is busy, and means under control of the second operator for disconnecting her telephone equipment from the seized trunk line simultaneously with the operation of the said signaling means.

circuit with the trunk line, means including a tone transmitting device an automatic switching means and a key for connecting the device to the seized trunk and for transmitting a tone to the first operator's position to indicate that a second operator's position is unattended and a means operated by said last mentioned means to prevent the second operator's equipment from being connected with the seized trunk.

30. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative responsive to the connection of said link circuit to one of said subscribers' lines to connect the link circuit with said trunk circuit, and means responsive thereto for automatically ringing the seized subscriber's line.

31. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative responsive to the connection of said

link circuit to one of said subscribers' circuits to connect the link circuit with said trunk circuit, and means responsive thereto for automatically ringing over said seized subscriber's line, and for automatically ringing over a second subscriber's line if the link circuit is transferred thereto from the first subscriber's line and not disconnected from the seized trunk.

32. A telephone system comprising trunk lines, an operator's telephone set, means for seizing any one of said trunks, means operative when a trunk is seized to connect the operator's set thereto, subscribers' lines, a link circuit for connecting with any one of said subscribers' lines, means operative when the trunk line and a subscriber's line are seized to connect the link circuit with the trunk line, means for disconnecting the link circuit from the trunk line when it is no longer seized, and signaling means operative to give a distinctive signal indication when the link circuit is no longer connected to the trunk line and another distinctive signal when the subscriber on the connected subscriber's line hangs up his receiver.

In witness whereof, I hereunto subscribe my name this 17th day of December A. D., 1923.

HENRY L. HOFFMANN.

DISCLAIMER

1,576,747.—*Henry L. Hoffmann, East Orange, N. J. TELEPHONE SYSTEM. Patent dated March 16, 1926. Disclaimer filed October 16, 1929, by the assignee, Western Electric Company, Incorporated.*

Hereby enters this disclaimer to the said claims of said Letters Patent which are in the following words to wit:

“1. A telephone system comprising trunk lines, an operator's telephone set, a first subscriber's line, means responsive to the connection of said first subscriber's line to any one of said trunks to connect the operator's telephone set thereto, a second subscriber's line, a link circuit for connecting to said second subscriber's line, and means operative upon the connection of said link circuit to said second subscriber's line to connect said link circuit to the said trunk circuit.

“2. A telephone system comprising trunk lines, an operator's telephone set, a calling line, means for connecting any one of said trunks to said calling line, an electromagnetic means operative when a trunk is seized to connect the operator's telephone set thereto, other subscribers' lines, a link circuit for connecting with any one of said other subscribers' lines, and a second electromagnetic means operative responsive to the connection of said link circuit to one of said other subscribers' lines for connecting the link circuit to the trunk line.”

“4. A telephone system comprising trunk lines, an operator's telephone set, means for seizing any one of said trunks, automatically operated means responsive thereto for connecting the operator's telephone set to the seized trunk, subscribers' lines, a link circuit for connecting with any one of said subscribers' lines, and a second automatically operated means responsive to the seizure of the subscriber's line by the link circuit and the seizure of the trunk circuit for associating the link circuit with the seized trunk line.

“5. A telephone system comprising trunk lines, an operator's telephone set, a first subscriber's line, means for connecting any one of said trunks to said first subscriber's line, means for automatically connecting the operator's telephone set to a trunk line when said trunk line is so seized, subscribers' lines, a link circuit for connecting with any one of said subscribers' lines, means for automatically connecting the link circuit to said seized trunk line when the link circuit has seized a subscriber's line.”

“7. A telephone system comprising trunk lines, an operator's telephone set, a first subscriber's line, means for connecting any one of said trunks with said first subscriber's line, means operative when a trunk is so seized to connect the operator's telephone set thereto, other subscribers' lines, a link circuit for connecting with any one of said other subscribers' lines, means operative responsive to the connection of said link circuit to one of said other subscriber's lines to connect the link circuit with said trunk line, and means operative when said other subscriber's line is seized for disconnecting the operator's telephone set from the seized trunk line.

“8. A telephone system comprising trunk lines, an operator's telephone set, a first subscriber's line, means for connecting any one of said trunks to said first subscriber's line, means operative when a trunk is so seized to connect the operator's telephone set thereto, other subscribers' lines, a link circuit for connecting with any one of said other subscribers' lines, means operative responsive to the connection of said link circuit to one of said other subscribers' lines to connect the link circuit with the trunk line, and means operated when the link circuit is connected to the seized trunk line to disconnect the operator's telephone set therefrom.

“9. A telephone system comprising trunk lines, an operator's telephone set, a first subscriber's line, means for connecting any one of said trunks with said first subscriber's line, means operative when a trunk is so seized to connect the operator's telephone set thereto, means to indicate the seizure of a trunk, other subscribers' lines, a link circuit for connecting with any one of said other subscribers' lines, and means operative responsive to the connection of said link circuit to one of said other subscribers' lines to connect the link circuit with the trunk line.”

“11. A telephone system comprising trunk lines, an operator's position at one end of said trunks, a first subscriber's line terminating at said position, an operator's position at the other end of said trunks, means at the first mentioned operator's position for connecting any one of said trunks, means operative when a trunk is seized to connect the second mentioned operator's telephone equipment thereto, means for indicating to the first mentioned operator when the second mentioned operator's equipment is associated with the seized trunk, other subscribers' lines, a link circuit at the second operator's position for connecting with any one of said other

subscribers' lines, and means operated responsive to the connection of said link circuit to one of said other subscribers' lines to connect the link circuit with said trunk line.

"12. A telephone system comprising trunk lines, an operator's position at one end of said trunks, an operator's position at the other end of said trunks, means at the first mentioned operator's position for seizing any one of said trunks, means operative when a trunk is seized for connecting the second mentioned operator's telephone equipment thereto, a means operated in response to the connection of the second mentioned operator's equipment to the seized trunk to transmit a momentary signal to the first mentioned operator's position over said seized trunk, subscribers' lines, a link circuit for connecting with any one of said subscribers' lines, and means operative when a trunk line and a subscriber's line are seized to connect the link circuit with the trunk line."

"15. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative responsive to the seizure of said trunk line and said subscriber's line to connect the link circuit with the trunk line, and means associated with the link circuit operative when the subscriber's line is seized to indicate to the operator that the subscriber's line is not otherwise engaged.

"16. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, and a visual signal in said link circuit operated when a subscriber's line is seized to indicate that the subscriber's line is not otherwise engaged.

"17. A telephone system, comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, and a visual signal in said link circuit operated when a subscriber's line is seized and before the trunk line is connected to the link circuit."

"19. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, means for disconnecting the link circuit from a trunk line when said trunk line is released, and a signal intermittently operated when the link circuit is released.

"20. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, and an indicating means operative when the link circuit is disconnected from the subscriber's line but still connected to the seized trunk line.

"21. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, and an intermittently operated signal actuated when the link circuit is disconnected from the subscriber's line but still connected to the seized trunk line.

"22. A telephone system comprising trunk lines, an operator's telephone set, means for seizing any one of said trunks, means operative when a trunk is seized to connect the operator's telephone set thereto, subscribers' lines, a link circuit for connecting with any one of said subscribers' lines, means operative when the trunk line and a subscriber's line are seized to connect the link circuit with the trunk line, and an intermittently operated visual signal actuated when the link circuit is disconnected from the subscriber's line but still connected to the seized trunk line."

"30. A telephone system comprising trunk lines, an operator's telephone set, means for seizing any one of said trunks, means operative when a trunk is seized to

connect the operator's telephone set thereto, subscribers' lines, a link circuit for connecting with any one of said subscribers' lines, means operative responsive to the connection of said link circuit to one of said subscribers' lines to connect the link circuit with said trunk circuit, and means responsive thereto for automatically ringing the seized subscriber's line."

"32. A telephone system comprising trunk lines, an operator's telephone set, means for seizing any one of said trunks, means operative when a trunk is seized to connect the operator's set thereto, subscribers' lines, a link circuit for connecting with any one of said subscribers' lines, means operative when the trunk line and a subscriber's line are seized to connect the link circuit with the trunk line, means for disconnecting the link circuit from the trunk line when it is no longer seized, and signaling means operative to give a distinctive signal indication when the link circuit is no longer connected to the trunk line and another distinctive signal when the subscriber on the connected subscriber's line hangs up his receiver."

[Official Gazette November 5, 1929.]
